UNITED STATES PATENT OFFICE.

HARRY E. HIXSON, OF AKRON, OHIO.

BOTTLE-RETAINER.

1,026,984.

Specification of Letters Patent. Patented May 21, 1912.

Application filed September 14, 1911. Serial No. 649,268.

To all whom it may concern:

Be it known that I, HARRY E. HIXSON, citizen of the United States, residing at Akron, in the county of Summit and State of Ohio, have invented certain new and useful Improvements in Bottle-Retainers, of which the following is a specification.

This invention comprehends certain new and useful improvements in bottle retainers and relates particularly to a self-locking retainer for milk or similar containing vessels.

The main object of this invention is to provide a bottle holder which will lock the bottle automatically in place when the bottle is inserted therein.

A further object is to provide a device of this character the mechanism of which is simple, durable and efficient, and entirely protected from the elements thus insuring the proper operation and extended service of the device.

A still further object is to provide a bottle retainer having coacting bottle engaging jaws controlled within a casing by an automatically operating spring detent or latch which can be released only by an authorized person.

Further objects will appear in the following description, it being understood that various changes in form, proportion and minor details of construction may be resorted to within the scope of the appended claims.

For a full understanding of the invention and the merits thereof, reference is to be had to the following description and the accompanying drawings in which:

Figure 1 is a perspective view of the bottle retainer with a bottle inserted therein; Fig. 2 is a horizontal, sectional view showing one end of the device with a bottle inserted, the other end being in a position to receive a bottle; Fig. 3 is a vertical sectional view with the parts in the same relation as in Fig. 2; and Fig. 4 is a transverse sectional view showing the detent or latch secured to the wall of the casing.

Corresponding and like parts are referred to in the following description and indicated in all the views of the accompanying drawings by the same reference characters.

This device is adapted to be used in connection with bottles preferably having a flange near the mouth thereof, and embodies

a casing 1, preferably open at the front and reinforced at the lower edge by a transverse brace 2 which also acts as an anchorage for a partition 3 which divides the casing into compartments A and B. A door 4 provided with a locking device 5 which engages a keeper 6 secured to the casing is adapted to inclose the open side of the casing, said door abutting against the brace 2 when in a closed position.

For the sake of clearness and brevity, the following description refers to one unit only of the device, the other unit being similarly constructed and operated. The under side of the casing 1 is partly inclosed by opposed, 70 coacting jaws or bottle-engaging plates 7 and 8, the former of which is rigidly secured to the casing and is provided with a recess 9 which is substantially semi-circular from the points *m* to *n* but thereafter said recess widens out and approaches the edges of the jaw or plate as at *o*. Coacting with the jaw 7 and opposed thereto is the movable bottle engaging jaw 8 which is pivoted to the casing wall by the pin 10 and is adapted to swing inwardly. Said jaw is formed with an opening 11 which is so disposed that when the jaws 7 and 8 are in engagement, when they are substantially in the same place, the opening 11 registers with the recess 9 and the two together thus form a substantially circular opening 12 which is slightly greater than the neck of a bottle below the flange. The opening 11 in the jaw 8 however, is large enough to permit the entrance of the neck of a milk bottle when the jaws 7 and 8 are not in engagement, being larger than the diameter of the bottle at the flange.

Within the casing and secured preferably to the partition 3 is a flat spring or detent 13 adapted to engage the jaw 8 on its upper face and lock it in engagement with the jaw 7. In order to hold the jaw 8 in a partially lowered position at which time it bears against the flat vertical face of the detent, a preferably coiled spring 14 encircling the pin 10 is secured at one end to the casing and at the other end bears against the jaw 8 thus tending to depress said jaw and keep the jaw in such a position as to readily receive the neck of a bottle in the opening 11.

For the purpose of gaining access to the casing 1 so that the detent 13 may be operated to release the jaw 8, said casing is pro-

vided with a lock controlled means of access, in this case the door 4 having a lock 5 but the device is not necessarily limited to this method of construction.

5 From the foregoing description in connection with the accompanying drawings, the operation of the improved bottle retainer will be apparent. The movable jaw 8 normally is in a partially raised position and 10 bears against the vertical face of the detent 13 being retained there by the action of the coiled spring 14. A bottle C having a flange D about its mouth, is pushed up past the fixed jaw 7 and against the movable jaw 15 8 which thereupon is raised until the flange of the bottle passes through the opening 11 in the jaw. The spring 14 then causes the jaw 8 to descend and aided by a downward pull on the bottle, the jaw 8 is forced past 20 the detent 13 and rests upon the fixed jaw 7 so that the openings in the two jaws register and closely encircle the neck of the bottle which is now suspended by its flange D. As a downward pull is exerted on the bottle the 25 lower end of the detent 13 will automatically engage the upper face of the jaw 8 and securely hold the jaws in contact thus locking the bottle in place so that it cannot be removed until the lock 5 is operated and the 30 door opened to permit the detent 13 to be released from engagement with the upper face of the movable jaw 8 thus allowing the jaw to be raised up and the bottle withdrawn. The jaw 8 now rests against the 35 detent 13 and in a position to receive another bottle.

The bottle retainer shown in the drawings is composed of two compartments, but the device is of course not limited to this construction as it might be made to accommodate a single bottle or a plurality of bottles as desired.

In order to entirely dispense with the necessity of attention to the retainer when 45 milk or other bottled goods are desired the door 4 or some other visible part of the retainer is provided with a pivoted dial 15 formed with a slot 16. Secured beneath the dial and concentric therewith are annularly 50 arranged quantitative characters which may be consecutively revealed through the slot 16, upon the rotation of the dial 15. Thus the characters designating the number of bottles desired is exposed and after this adjustment is made no further attention is de- 55

manded until it is desired to remove the bottles from the retainer.

It is of course to be understood that the bottle retainer is adapted to be attached to some support so as to leave the under side 60 accessible. It is plain that it will require no more time to place the milk or other bottles in retainers of this kind than would be demanded to place them carelessly where they would be subjected to theft and exposed to 65 dirt and other elements. Furthermore, the placing of the simple mechanism within a casing protects it from injury and insures the continued operation thereof. The mouth of the bottle is also protected by the inclosing casing making it impossible for dirt, 70 water and foreign matter to gather around the mouth of the bottle and thus come in contact with the contents thereof.

Having thus described the invention what 75 is claimed is:

1. A bottle retainer comprising a casing having its bottom provided with a bottle receiving opening, said opening having diverging side walls, a jaw pivoted within the 80 casing adjacent the bottom thereof and having a similar but reversely arranged opening, means at one side of said jaw tending to force the same against the bottom, and means at the opposite side of the jaw to normally support the jaw off the bottom and to lock the jaw against the bottom after it has been engaged by the bottle.

2. A bottle retainer comprising a casing having a bottle receiving opening in its bottom, a jaw pivotally mounted within the casing and having a bottle receiving opening adapted to co-act with the bottle receiving opening in the bottom of the casing, means at the pivotal support of the said 90 jaw to force the said jaw against the bottom of the casing, and a detent within the casing arranged in the path of the free edge of the jaw whereby the said detent will normally support the jaw off the bottom of the 95 casing and will project over the free edge of the jaw when the same has been drawn against the bottom of the casing by an inserted bottle.

In testimony whereof I affix my signature in presence of two witnesses.

HARRY E. HIXSON. [L.S.]
